ATTORNEY.

UNITED STATES PATENT OFFICE

122,140

DESIGN FOR AN EMBROIDERED FABRIC

Alex Grossman, Jersey City, N. J.

Application July 19, 1940, Serial No. 93,783

Term of patent 3½ years

To all whom it may concern:

Be it known that I, Alex Grossman, a citizen of the United States, residing at Jersey City, Hudson County, and State of New Jersey, have invented a new, original, and ornamental Design for an Embroidered Fabric, of which the following is a specification, reference being had to the accompanying drawing, forming part thereof, wherein the figure is a plan view of an embroidered fabric, showing my new design.

I claim:

The ornamental design for an embroidered fabric, substantially as shown.

ALEX GROSSMAN.
